UNITED STATES PATENT OFFICE.

WILLIAM J. KEEP AND CHARLES WIPFLER, OF DETROIT, MICHIGAN, AS
SIGNORS TO THE MICHIGAN STOVE COMPANY, OF SAME PLACE.

DESIGN FOR A COOKING-STOVE.

SPECIFICATION forming part of Design No. 16,830, dated August 3, 1886.

Application filed May 10, 1886. Serial No. 201,749. Term of patent 7 years.

To all whom it may concern:

Be it known that we, WILLIAM J. KEEP and CHARLES WIPFLER, of Detroit, in the county of Wayne and State of Michigan, have invented new and useful Improvements in Designs for Cooking-Stoves and Parts thereof; and we do hereby declare that the following is a full, clear, and exact description thereof, reference being had to the accompanying drawing, which to form a part of this specification.

This design relates to cooking stoves and parts thereof, as more fully hereinafter described, and shown in the accompanying photographic illustration.

A represents the legs of the stove, which are of the usual form, with a semicircular recess formed on each side of the front or presented face, which, with the balance of the leg, is surrounded by a raised band or flat or oval bead, as shown. The front face of the leg may be ornamented as desired.

B is a screen-plate having semicircular ends. This plate is ornamented by a series of rosettes of a floral design connected together by an intertwining line of stems and leaves. Under each end of this plate it is widened, as shown, and the presented face ornamented with scroll-work of what is ordinarily termed a "shell pattern," as shown, such enlargements having the appearance of bracket-supports for the plate itself, the ornamentation of which may be likened to an extended floral wreath.

C is the oven-door, made in the outlines shown, convex in form on its presented face. The ornamentation of this door is as follows: An interrupted floral wreath on three sides incloses a space, and across the top of this space so partially inclosed appears a representation of a flame and completing the inclosure of the space. Around the knob of the door the door-plate has a representation of a flame having the appearance of springing from a central fire. The door-jamb, below the oven-door, is formed in the shape of an elongated raised panel, C', the ends and bottom edge of which join in graceful lines the side plate of the stove, of which it forms an integral part. Upon this panel may appear the name of the manufacturer, if desired. The hinges G are ornamented with horizontal bands or beads, with an orna-

mental top terminal, that shown being the representation of the flaming end of a burning torch.

D is a plate having its upper and lower edges parallel and its front end on a curved line, as shown, the said plate forming an extension of the side of the stove to the front, between the hearth and the bottom plate of the stove, and its ornamentation consists of scroll-work of the pattern known as "shell-work," the rays or scrolls of which radiate from a common center, as shown.

E is a plate rectangular in form on three sides, with its other or rear side on a curved line, and forms a front extension of the door-jamb above the hearth proper of the stove and the hearth below the combustion-chamber door, as shown. The ornamentation of this plate consists of a floral ornamentation, as shown.

F is the end door, leading into the combustion-chamber of the stove. Its ornamentation consists of a central rosette surrounded by a ring, which in turn is surrounded by radial corrugations alternating with radial ribs, as shown. Partially below this ornamentation, and pointing toward each of the lower corners of the door-plate, there is some ornamental scroll-work, connected with which are interrupted parts of a ring, inclosing, as shown, the central figure.

H is the end plate of the hot-water reservoir and of the water-closet below said reservoir. There are two sets of these plates, one for each end of the closet. In the illustration the lower plate is formed as a door to the warming-closet, while the lower portion of the upper plate is a raised panel, forming with the door-plate, when the latter is closed, a long rectangular panel with a slightly-convex face. As a panel, its ornamentation consists of two transverse bands, one near its lower end and the other at the upper edge of the door-section of the panel, thereby virtually subdividing the panel in its entirety into three horizontal panels of unequal size, with the larger one in the center. In the upper panel there is shown a floral design, just above the upper of the two bands and central between the sides of the plate. In the upper corners of the central panel are shown the ends of streamers,

and near the center of this panel there is shown in bas-relief a representation of a human face surrounded by a ring, immediately below which there is shown part of a floral wreath.

5 The front door of the hearth of the stove is of a peculiar design, of which I represent the plates which form each end of such door, the front being cast integral with such end plates. These end plates are straight on their rear surfaces where they meet the door frame or jambs. The front surfaces are parallel with the rear surfaces from the bottom to nearly half-way to the top. Thence they project forward at an upwardly-turned angle of about forty-five degrees, and thence curve upwardly and rearwardly to the original vertical plane.

10 J is the reservoir-top, which consists of a downwardly-projecting plain flange band in continuation of a similar band upon the stove-top, and is surmounted by successive ogees and bands alternately, which decrease in size and have an enlargement at the front side to embrace the pipe-collar.

What we claim as our invention is—

15 1. In a design for a cooking-stove, the screen-plate B, ornamented with a series of rosettes and intertwining stems and leaves, and at each end with scroll-work of a shell pattern, substantially as shown and described.

20 2. In a design for a cooking-stove, the legs A and the screen-plate B, ornamented with

rosettes and intertwining stems and leaves, and with widened ends ornamented with scroll-work of a shell pattern, as shown.

3. In a design for a cooking-stove, the oven-door plate C, ornamented by a wreath containing rosettes and inclosing three sides of the name-space, the inclosure being completed on its upper side by the representation of a flame, as shown and described. 35

4. In a design for a cooking-stove, the extension-plate D, ornamented with scroll-work of a shell pattern, as shown and described. 40

5. In a design for a cooking-stove, the extension-plate E, of the configuration shown, and ornamented with a floral design containing a rosette, as shown and described. 45

6. In a design for a cooking-stove, the plate F, nearly or quite rectangular in outline, and ornamented with a rosette, as shown and described. 50

7. In a design for a cooking-stove, the rectangular panel H, divided into two panels of unequal size by an ornamental transverse band, and each panel ornamented with rosettes, substantially as shown and described. 55
